UNITED STATES PATENT OFFICE.

MANES HAMBURGER, OF WASHINGTON, DISTRICT OF COLUMBIA.

COMBINED BUTTON AND FASTENER.

SPECIFICATION forming part of Letters Patent No. 310,273, dated January 6, 1885.

Application filed April 7, 1884. (No model.)

To all whom it may concern:

Be it known that I, MANES HAMBURGER, a citizen of the United States, residing at Washington city, in the District of Columbia, have invented certain new and useful Improvements in Combined Button and Button-Fastener; and I hereby declare the following to be a full, clear, and exact description of the same, reference being had to the accompanying drawings, in 10 which—

Figure 1 is a perspective view of a button and fastener embodying my invention. Fig. 2 is a vertical central section of the same. Fig. 3 is a similar view showing a modified form of 15 fastener.

Like letters refer to like parts wherever they occur.

My present invention relates to the construction of that class of buttons other than those 20 which are secured to the garment by thread, and to the means or fasteners for securing the button to a garment. Where the button is secured to the fabric by sewing, as in the ordinary manner, the thread forms a flexible neck or stem 25 between the button and fabric, which in a great measure relieves the fabric of undue strain, and as a result the fabric is seldom or never torn. On the contrary, in the case of all buttons secured by what are now termed “button- 30 fasteners,” the strain is brought directly on the fabric, and the common experience is, that the fastener is speedily torn out, carrying with it the fabric and mutilating the garment. The cause of this tearing out of the fabric is be- 35 cause the hold of the fastener upon the fabric is not only circumscribed, but rigid, and the connection between the shell of the button and the fastener is also rigid or non-elastic in its nature, so that the whole strain is brought 40 upon the clamped or circumscribed portion of the fabric.

The object of the present invention is, therefore, the production of a combined button and fastener which will relieve the fabric of the 45 rigid strain upon the circumscribed or clamped portion, and, as near as possible in such a device, operate like the old hand-sewed button.

I will now proceed to describe specifically 50 one manner of carrying out my invention, so that others skilled in the art to which it ap- pertains may apply the same.

In the drawings, A indicates the button; B, its flexible connection with the fastener or stem; C, the fastener, and D the fabric to which the button is attached. The stem B may 55 be composed of the outer flexible fabric, cloth, leather, or rubber, as the case may be, and, if required to give body or stiffness to the same, an inner core, 2, of leather, cork, rubber, or like material. The flexible material compos- 60 ing the stem will extend into the space between the shell 3 and collet 4, and will be clamped and held between the same in the well-known manner of forming buttons. The flexible material of the stem will also be secured 65 to the fastener in any suitable manner, preferably as shown in the accompanying drawings—viz., by an annular collar, 5, (corresponding to the collet of a button,) and a plate or disk, 6, (corresponding to the shell of a but- 70 ton,) the parts 5 and 6 being united at their peripheries to clamp the flexible material. To this base-plate 6 the fastener is secured, and its general character is immaterial so far as the first part of the invention is concerned; 75 therefore I have shown both a separable, Fig. 2, and a permanent, Fig. 3, fastener; but as a matter of choice I prefer the separable fastener, which is constructed by forming on or attaching to the base-plate 6 a projecting screw- 80 peg, 7, of such length as will pass through the class of goods with which the button is de- signed to be used. In conjunction with said screw-peg I employ a nut or annular threaded washer, 8, over which is sprung a cap, 9, or 85 like means for concealing the end of the screw- peg.

In Fig. 3, which shows a permanent fastener, the base-plate 6 is provided with projecting points 7^x, and, instead of a nut, a slotted 90 clamping-disk, 8^x, is used.

In the case of the separable fastening, Fig. 2, a small opening may be made in the fabric for the passage of the screw-peg, and the button may be secured by applying and screwing 95 home the nut 8, while in case of the permanent fastening the points 7^x may be forced through the fabric, passed through the clamping-disk 8^x, and turned down against the disk.

In case of a button having a flexible stem-connection with the fastener, and of the general character hereinbefore specified, it will 100

be observed that no rigid strain or sudden pull is brought to bear on the fastener and fabric, but on the contrary the flexible neck permits the button to yield to movements of the body 5 or garment, and the fabric is thus preserved from being torn.

I am aware that the metallic base and top plates of a stud, collar, or cuff button have been connected by a solid india-rubber shank 10 or stem, in order to overcome the liability of fracture where a rigid stem is used, and also to avoid unpleasant pressure against the body of the wearer due to a rigid shank in such articles; and I am also aware that in a separable 15 button having a metallic head and clamp connected by a rigid stem a tubular rubber spring has been slipped upon the rigid stem to act as a spring in securing the parts to each other and to the fabric or garment, and do not herein 20 claim the said constructions, because in the former the base-plate of the stud is never clamped to the garment, and therefore the flexible neck has no function in relieving the

garment from strain brought directly on a clamp, while in the latter the rigid stem, which 25 connects the button and clamp, transmits the strain to the garment, notwithstanding the compressible rubber tube which surrounds the rigid stem.

Having thus described the nature and advantages of my invention, what I claim, and desire to secure by Letters Patent, is—

As an improved article of manufacture, a combined button and fastener composed of a button, a flexible shank, and a rigid shoe, 35 constructed substantially as described, and adapted to receive a suitable fastener, substantially as and for the purposes specified.

In testimony whereof I affix my signature, in presence of two witnesses, this 7th day of April, 40 1884.

MANES HAMBURGER.
